CLAIM

The ornamental design for a gift bag, as shown and described.

DESCRIPTION

FIG. 1 is a first perspective view of the gift bag in a closed configuration showing my new design;

FIG. 2 is a left side view thereof;

FIG. 3 is a right side view thereof;

FIG. 4 is a front view thereof;

FIG. 5 is a back view thereof;

FIG. 6 is a top view thereof;

FIG. 7 is a bottom view thereof;

FIG. 8 is a perspective view of the gift bag in an open configuration; and,

FIG. 9 is another perspective view in an open configuration. The broken lines shown in the drawings are for the purpose of illustrating portions of the gift bag that form no part of the claimed design.
